FIG. 5.

JOHN SAMUEL BEDFORD
INVENTOR
by C. James Cottrell, ATTORNEY

UNITED STATES PATENT OFFICE

JOHN SAMUEL BEDFORD, OF TWICKENHAM, ENGLAND

DOOR ATTACHMENT FOR VEHICLES

Application filed November 23, 1931, Serial No. 576,638, and in Great Britain December 1, 1930.

This invention relates to attachments for doors and is applicable, for example, to doors for road vehicles and for similar purposes.

The object of the invention is to provide an attachment for holding the free edge of the door so as to form an additional support therefor in order to avoid or minimize rattling and vibration of the door.

A further object of the invention is to provide an attachment embodying a socket and plug one associated with the door and the other with the fixed support therefor, and when the door is in the closed position said plug being entered into and held within said socket.

A still further feature of the invention is to provide a resiliently mounted thimble within a socket associated with the door or with the fixed support therefor into which thimble there is adapted to be entered when the door is closed a projecting member or plug associated with the fixed door support or the moving door itself respectively.

A still further object of the invention is to provide means for adjusting the effective internal diameter of a resiliently mounted thimble located within the socket and into which there is adapted to be entered when the door is closed a projecting member so as to hold the door in such a manner that rattling and vibration is eliminated.

Further objects will be apparent after consideration of the description of the accompanying drawing illustrating embodiments of the invention by way of example.

Fig. 1 is a perspective view of the component parts of the device in accordance with one form of the invention applicable to a pivotally mounted door, the position of the door and its supporting frame being indicated by dotted lines.

Fig. 2 is a vertical section through the parts of the device with the door in the closed position.

Fig. 3 is a perspective view of the thimble. Fig. 4 illustrates a resiliently expandable and contractible plug and

Fig. 5 shows a method for positively causing expansion and contraction of the plug.

Referring to the accompanying drawing,

the device consists essentially of two parts lettered respectively A and B, the part A being shown in Fig. 1 attached to the vertical edge of the movable door, while the part B is secured to the supporting frame of the door. The part A embodies a projecting plug extending in a direction more or less parallel with the door edge and in order to lessen the amount of overhang thereof from the edge of the door the vertical face of the part A may be recessed as indicated at 2. The portion A conveniently comprises a metal casting, the plug 1 being formed integrally therewith or being separately attached in any suitable manner, and is attached to the vertical edge of the door by means of suitable screws passing through counter-sunk apertures in the vertical face thereof.

The part B is of any suitable shape, and embodies, at approximately the middle of its length, a hollowed housing C conveniently cast integrally therewith. Fig. 2 of the drawing is a section through this housing and from the figure it will be seen that a thimble 3 formed of metal or other material and which is split longitudinally, is accommodated within said housing. Fig. 3 illustrates the thimble 3 in detail and shows same split longitudinally at 4 to impart resilience thereto. The metal thimble however may be rendered contractible in any other convenient manner, for example it might be formed with a spirally arranged groove or slot, or it might be provided with serrations for the same purpose.

Mounted upon said thimble and located conveniently between end flanges 5 at each end thereof, is a resilient sleeve or layer 6 which is of such a diameter that it may readily be inserted into the housing C. The sleeve or layer 6 may conveniently be composed of India-rubber. The end of the housing into which the projecting plug 1 associated with the part A is entered is, in the construction illustrated, inturned at its edge to a suitable extent to constitute an abutment which locates the position of the sleeve or layer 6 surrounding the thimble, as will be clearly seen from Fig. 2 of the drawing. The proportion of the outer flanges of the

thimble 3 is such that there is a small free space 9 left between the outer edge of the flange and the inner edge of the inturned portion of the housing when the thimble is 5 inserted in position.

The other end of the housing is screw threaded and a screw cap 7 may be adapted to screw into said screwed portion, the cap 7 conveniently embodying an annular 10 pending rim 8 at its under side which serves to come into contact with the lateral edges of the sleeve 6 mounted upon the metal thimble 3 and it will readily be understood that when the cap 7 is screwed into the housing 15 the depending annular flange 8 of the said cap compresses the sleeve 6 and on account of same being confined with the rigid metal housing C, the thimble 3 yields and the effective internal diameter thereof is reduced 20 to grip the plug 1 associated with the part A of the device more tightly. In this manner by adjusting the position of the screw cap 7 it is possible to obtain a simple adjustment 25 of the gripping action exerted by the thimble 3 upon the projecting plug 1 and it will readily be understood that there is no metal connection between the parts A and B when the door is in the closed position, the plug 1 being located within the thimble 3, which 30 is supported solely by the sleeve 6 or layer surrounding same and thus any possibility of vibration or rattling is effectively avoided.

In the construction illustrated in Figs. 4 and 5 means are provided for rendering the 35 plug expansible and contractible and these arrangements may be utilized in connection with a non-contraction thimble. In Fig. 4 the plug 21 is provided with two diametrical slots 10 so as to form a plug of a self expanding nature to secure an effective grip within the thimble. In Fig. 5 only one slit 10' is shown but a cone-headed screw 11 is located within an axial aperture in the plug 31 to permit an adjustment of the external diameter 45 of the plug by screwing the part 11 into or out of the plug.

In the construction illustrated in Fig. 1 it is assumed that the part A is associated 50 with a door which is mounted to swing upon a vertical axis but the invention may obviously be utilized in connection with doors of different kinds, such as to sliding doors. Further it will be immediately evident that the positions of the parts A and B relatively 55 to the door and the supporting frame may be reversed, that is to say, the part A with the projecting plug 1 may be associated with the supporting frame while the socket portion B is associated with the movable part 60 of the door.

I claim:—

1. An attachment for doors comprising a socket and plug one associated with the moving door itself and the other with the fixed 65 support therefor, a thimble within said sock-

et to engage the plug, a layer of resilient material on said thimble and means for adjusting the effective internal diameter of said thimble.

2. An attachment for doors comprising a 70 socket and plug, one associated with the moving door itself and the other with the fixed support therefor, a thimble within said socket to engage said plug, a non-metallic mounting for said thimble and means for compressing said non-metallic mounting so as to vary the gripping effect of said thimble upon the plug.

3. An attachment for doors comprising a 75 socket and plug, one associated with the moving door itself and the other with the fixed support therefor, a split thimble to engage the plug, a layer of resilient material carried on said thimble and means for compressing said resilient layer axially to vary the effective internal diameter of the thimble and to adjust its gripping effect on the plug.

4. An attachment for doors comprising a 80 socket and plug, one associated with the moving door itself, and the other with the fixed support therefor, a thimble within said socket having out-turned flanges at each end, a sleeve of resilient material carried on said thimble between said out-turned flanges and a screwed member working within said housing to compress said resilient sleeve axially 85 thereby to adjust the effective internal diameter of the thimble and consequently adjust its gripping effect upon the plug.

5. An attachment for doors comprising a 90 socket having a hollow bore with an inturned flange or rebate at one end and a plug to enter within said socket, said socket and plug being mounted one upon the moving door and the other upon the fixed frame therefor, 95 a thimble within said socket, a sleeve of resilient material on said thimble, said sleeve being lodged against the inturned flange in the bore, a screwed member at the opposite end of said bore adjustable to compress the 100 sleeve of resilient material axially therein and means whereby said compression effects an adjustment of the gripping action of the thimble upon the plug.

6. An attachment for doors comprising a 115 socket having a hollow bore with an inturned flange or rebate at one end and a plug to enter within said socket, said socket and plug being mounted one upon the moving door and the other upon the fixed frame therefor, 120 a thimble within said socket, out-turned flanges at each end of said thimble, a sleeve of rubber upon said thimble, said rubber sleeve being lodged against the inturned flange of the bore in said socket, a screw threaded portion at the opposite end of said bore and a screwed member working therein having a projecting rim to engage the side 125 of the rubber sleeve opposite to that engaged by the flanged end of the bore.

7. An attachment for doors comprising a socket having a hollow bore with an inturned flange or rebate at one end and a plug to enter within said socket, said socket and plug being mounted one upon the moving door and the other upon the fixed frame therefor, a longitudinally split thimble, an out-turned flange at each end of said thimble, a resilient sleeve mounted thereon projecting radially from the tip of said flanges for a substantial distance, said rubber sleeve being lodged against the inturned flange in the bore so that the thimble is not in metallic contact at any place with the socket, a screwed portion at the opposite end of said bore and a screwed member rotatable therein having a projecting rim-like annulus to engage the side edge of the rubber sleeve and compress same axially on rotary adjustment of said screwed member, whereby adjustment of the internal diameter of the thimble can be effected.

8. A door attachment comprising a socket and plug the axes of which are located substantially normal to the planes of the parts to which they are attached, one being associated with the moving part of the door and the other with the fixed support therefor and being entered one within the other when the door is closed, a thimble within said socket, a sleeve of resilient material mounted on said thimble, an inturned flange at one end of said socket to locate said sleeve and to hold same in position without the thimble coming into metallic contact with the socket, screw means at the opposite end of said socket to compress said sleeve axially and means whereby said axial compression effects an adjustment of the effective internal diameter of the thimble.

40 9. A door attachment comprising a socket and plug, one associated with the moving part of the door and the other with the fixed support therefor, a thimble resiliently mounted within said socket and not in metallic contact therewith and means for adjusting the effective diameter of said plug.

50 10. A door attachment comprising a socket and a split resilient plug, one associated with the moving part of the door and the other with the fixed support therefor, a thimble within said socket, a sleeve of resilient material around said thimble to form the sole support therefor and screw means for holding the thimble in place.

55 JOHN SAMUEL BEDFORD.
